United States Patent Office

MARTIN J. MELLYN, OF ROXBURY, MASSACHUSETTS.

Letters Patent No. 72,663, dated December 24, 1867.

IMPROVED MODE OF SECURING FELLOES.

The Schedule referred to in these Letters Patent and making part of the same.

TO ALL WHOM IT MAY CONCERN:

Be it known that I, MARTIN J. MELLYN, of Roxbury, in the county of Norfolk, and in the State of Massachusetts, have invented certain new and useful Improvements in Mode of Securing the Joints of Felloes for Wheels; and do hereby declare that the following is a full, clear, and exact description thereof, reference being had to the accompanying drawings, and to the letters of reference marked thereon.

In the annexed drawings, making part of this specification, A A represent two parts of felloes for wheels, which meet at the line α α . B represents a metallic plate, which is made just the width of the felloe, and four or five inches in length. This plate has, at its centre, a bolt, C, and on each side of this bolt, a rib, a a . The bolt C passes through a hole made in the felloe, where the two parts join. Near the extremities of the plate B, are holes, and through these and the felloe pass the bolts F F. H represents the usual clip or plate upon the inside of the point. D represents the tire of the wheel.

The improvement in this case, it will be seen, consists in the use of the plate B with its bolts, for covering and securing the joint of the two parts of the felloe. The plate B is let into the felloe, so that its outer face will be flush with the wood at its ends. When the tire is shrunk on, it fits snugly over the plate B without any jog or elevation. This plate will prevent the giving down of the ends of the felloe, which is now so common in the ordinary wheel.

Having thus fully described my invention, what I claim as new, and desire to secure by Letters Patent, is—

The metallic plate B, having a bolt, C, and ribs a a , when constructed and used in the manner and for the purposes set forth.

In testimony that I claim the foregoing, I have hereunto set my hand, this 23d day of October, 1867.
